(57) **CLAIM**

The ornamental design for a lens for light detection element as shown and described.

DESCRIPTION

FIG. 1 is a front view of a lens for light detection element of a first embodiment of our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front perspective view thereof;

FIG. 8 is a rear perspective view thereof;

FIG. 9 is a sectional view taken along the line 9-9 of FIG. 1;

FIG. 10 is a sectional view taken along the line 10-10 of FIG. 1;

FIG. 11 is an enlarged view showing a portion of FIG. 10 defined by lines 11-11 and 11'-11';

FIG. 12 is a front view of a lens for light detection element of a second embodiment of our new design;

FIG. 13 is a rear view thereof;

FIG. 14 is a top plan view thereof;

FIG. 15 is a bottom plan view thereof;

(Continued)

FIG. 16 is a right side view thereof;
 FIG. 17 is a left side view thereof;
 FIG. 18 is a front perspective view thereof;
 FIG. 19 is a rear perspective view thereof;
 FIG. 20 is a sectional view taken along the line 20-20 of FIG. 12;
 FIG. 21 is a sectional view taken along the line 21-21 of FIG. 12; and,
 FIG. 22 is an enlarged view showing a portion of FIG. 21 defined by lines 21-21 and 21'-21'.
 The features shown in broken lines depict environmental subject matter only and form no part of the claimed design.

1 Claim, 22 Drawing Sheets
